United States Patent Office

Des. 233,899
Patented Dec. 10, 1974

233,899

ROTARY AMUSEMENT DEVICE

Jacob W. Burkart, Cincinnati, Ohio, and John F. Mayer, Fort Thomas, Ky., assignors to General Mills Fun Group, Inc.

Filed Apr. 30, 1973, Ser. No. 355,983

Term of patent 14 years

Int. Cl. D21—02

U.S. Cl. D34—5 G

FIG. 1 is a perspective view of a rotary amusement device illustrating our new design;

FIG. 2 is a front elevational view partly in section;

FIG. 3 is a top plan view thereof; and

FIG. 4 is a bottom plan view thereof.

We claim:

The ornamental design for a rotary amusement device, substantially as shown.
